UNITED STATES PATENT OFFICE.

CHARLES T. RIDGELY, OF SPRINGFIELD, OHIO, ASSIGNOR TO THE STANDARD TRIMMER COMPANY, OF SPRINGFIELD, OHIO, A CORPORATION OF OHIO.

CUTTING-TOOL.

No. 908,499.

Specification of Letters Patent.

Patented Jan. 5, 1909.

Application filed December 26, 1905. Serial No. 293,196.

To all whom it may concern:

Be it known that I, CHARLES T. RIDGELY, a citizen of the United States, residing at Springfield, in the county of Clark and State 5 of Ohio, have invented certain new and useful Improvements in Cutting-Tools, of which the following is a specification, reference being had therein to the accompanying drawings.

10 This invention relates to cutting tools, and, more specifically, to cutting tools designed for use in cutting paper, cloth, etc., being more specifically designed as a trimming tool for the purpose of trimming the 15 edges of wall paper, window shades and the like, in connection with a straight-edge for guiding the same.

One of the objects of my present invention is to provide a construction whereby the 20 power applied to the head for the purpose of depressing the head and the cutting disk carried thereby to bring the cutter to its work will act upon the trimmer as a whole in such a way as to also cause it to move along 25 its prescribed path, thereby facilitating the operation of the device and causing it to start upon its travel before or at the same time that it begins to cut.

A further object of this feature of my invention is to so transmit the power applied 30 by the operator's hand to the head as to cause it to act upon the cutter with a maximum of efficiency, to obtain the best results with the least exertion.

35 Another object of my invention is to so support the gage portion of the trimmer relatively to the guide of the straight-edge as to reduce the amount of friction between the two at their points of lateral contact and 40 permit a more accurate fitting of the parts in this respect.

A further object of my present invention is to maintain the trimmer in a position at 45 right angles to the plane of the straight-edge, preventing tilting and rocking and insuring the movement of the cutting disk in a plane at right angles to the surface of the material on which it operates.

Another object of my present invention is 50 to provide a bearing or support for the cutting disk and its arbor in the head which will accurately position the disk with respect to the straight-edge and trimmer without requiring the employment of an adjustable end

bearing or abutment for the arbor, or frictional contact of the cutting disk against the straight-edge, while at the same time the removal of the cutting disk and its arbor from the trimmer, and its replacement therein, may be readily effected. 55

Yet another object of my invention is to do away with all frictional contact between the head and the parts carried thereby on the one hand and the straight-edge on the other hand, at the same time making provision 60 for avoiding excessive friction between the head and the gage, so that the guiding functions are confined to the gage and the guide on the straight-edge, and the head, with its cutter, is adapted to move relatively to 65 these parts with a minimum of friction.

To these and other ends my present invention consists in certain novel features which I will now proceed to describe, and will then particularly point out in the claims. 70

In the accompanying drawings, Figure 1 is a top plan view of a structure embodying my invention in one form; Fig. 2 is a face view or front elevation of the same; Fig. 3 is an elevation of the same viewed from the opposite side; Fig. 4 is an inverted plan view of the trimmer proper, detached; Fig. 5 is a detail sectional view, illustrating the bearing 80 for the arbor of the cutting disk, the same being in section upon the line $x-x$ of Fig. 2 and 85 looking in the direction of the arrows; Fig. 6 is a detail sectional view, taken transversely through the central portion of the gage in a vertical plane, illustrating the bearings of the 90 gage upon the guide; Fig. 7 is a detail sectional view, taken on the line $y-y$ of Fig. 2 and looking in the direction of the arrows; Fig. 8 is a plan view, illustrating a modification; Fig. 9 is an elevation of the inner face of the structure shown in Fig. 8; Fig. 10 is a view 95 similar to Fig. 8, illustrating yet another modification; and Fig. 11 is a view, similar to Fig. 9, of the structure shown in Fig. 10.

Referring to the said drawings, 1 indicates a straight-edge, of any approved construction, having a guide along one of its margins. This guide is preferably formed by the application to the body of the straight-edge of a metallic guide strip comprising a vertical portion 2 having a lateral guide surface 3, 105 and a horizontal portion 4, having a top bearing surface 5. The horizontal portion of this metallic guide strip overhangs the body

of the straight-edge, which is preferably grooved, as indicated at 6, to effect this result, and the edge of the horizontal portion 4 constitutes a second lateral guiding surface 5, disposed in a direction opposite to the guiding surface 3. The under surface of the projecting margin of the horizontal portion 4 of the guide strip constitutes a contact surface 8, disposed in a direction opposite to that of the bearing surface 5 on the upper side of said strip. The guide thus formed receives and guides the gage portion 9 of the trimmer, which is held in such relation to the guide and straight-edge as to always stand vertically with respect to the same, assuming the straight-edge to be horizontal. The gage 9 comprises a body portion, the under face of which, indicated at 10, forms a bearing surface which travels on the top bearing surface 5 of the guide, on which it rests and is supported. On the front face of the gage there is provided at each end a downward extension 11, these downward extensions forming guiding members which coöperate with the guiding surface 3 on the outer face of the vertical portion 2 of the metallic guide strip. The central portion of the gage has on its inner or rear side an extension 12, which, as shown in fig. 6, extends downward past and coöperates with the lateral guiding surface 7 on the opposite side of the guide, said extension 12 constituting a guiding member engaging the guiding surface on one side of the guide, while the guiding members 11 engage the lateral guiding surface on the other side of the guide. Preferably, these guiding members are provided with bearing rollers which contact with the guiding surfaces and thereby prevent excessive lateral friction between the gage and guide. In the present instance, I have shown each guiding member 11 as terminating in a lug 13, apertured for the reception of a pivot screw 14, on which is mounted a roller 15. Similarly, the guiding member 12 is apertured for the reception of a pivot screw 16, on which is mounted a bearing roller 17. The rollers 15 thus bear on one side of the guide at points which are comparatively widely separated, while the roller 17 bears upon the opposite side of the guide at a point about midway between the bearing points of the two opposing rollers, thereby giving effective support and guidance to the gage. The guiding member 12 has a portion 18 which extends under the projecting margin of the horizontal portion 4 of the guide strip, engaging with the contact surface 8 on the under side thereof to hold the gage down upon the guide. As already stated, it is desirable that the gage should always be at right angles to the plane of the straight-edge, since the gage is, in the present instance, provided with bearing or contact surfaces which guide the movements of the head and of the cutting disk

carried thereby. Since, however, the gage engages under the guide on one side only, there is a tendency to tilt laterally away from the side not thus engaged, in case pressure is so applied to the trimmer as to cause such a tilting tendency. I provide means for overcoming this tilting tendency by the provision of a separate contact or bearing on the inner side of the gage, the same being in sliding contact with the straight-edge and serving to resist this tilting tendency. Preferably, this anti-tilting contact is a resilient one, so as to act at all times to maintain the gage in upright position, and I also prefer to make the contact a rolling one, so as to diminish friction as far as possible. The construction which I prefer for this purpose is that illustrated more particularly in Figs. 1 and 2, in which the guiding member 12 on the inner side of the gage has an extension 19, slotted horizontally, as shown at 20, to receive the end of a leaf spring 21, which is secured therein by a screw 22. The free end of the spring has mounted in it a roller 23, which is held in contact by the spring with the upper surface of the body of the straight-edge 1. The reaction of the spring 21 exerts an upward pressure on the projection 19, and holds the gage in a vertical position, or at right angles to the plane of the straight-edge, with the rollers 15 parallel with the guiding surface 3, so that the head moves in a plane at right angles to the surface operated on, and the cutting disk moves in a similar plane. This anti-tilting bearing may be otherwise constructed, however, and in Figs. 8 and 9 I have shown the same as consisting of a stud 24, secured in a recess in the guiding member 12 by means of a transverse pin 25, or in any other suitable manner, and having secured to its projecting portion one end of a leaf spring 26, the other end of which carries a roller 27 to bear upon the guide. The connection between the spring and stud may be effected by bending the end of the spring around the stud and securing it by a screw 28, or in any other suitable manner.

Yet another form of the anti-tilting guide is shown in Figs. 10 and 11, in which construction the guiding projection 12 is provided in its under side with a seat 29, in which is secured by a screw 30 one end of a leaf spring 31, the other end of which is rounded or curved, as indicated at 32, and bears upon the bottom of the groove 6, in which it travels. Other modifications of this structural feature will readily suggest themselves.

The head, indicated as a whole by the reference numeral 33, is supported and guided entirely by the gage, which latter is provided with vertical bearing surfaces 34, against which fit similar bearing surfaces 35 on the inner face of the head. It will be

observed that the guiding projections 11, on which the bearing surfaces 34 are in part formed, extend downward between the head and the outer or front face 3 of the straight-edge guide, from which it will be seen that the head is not guided by contact with said face of the straight-edge guide, as is usually the case in structures of this character. The head is provided with slots 36 and 37, 5 through which project parts supported by the gage, to permit the head to move up and down relatively to the gage and guide the same during its movement. The slots 36 and 37 are located at the two opposite 10 ends of the head and gage, so as to be on opposite sides of the axis of the cutting disk, hereinafter referred to, and said slots are inclined downward in the direction of movement of the trimmer when at work. Preferably, the angle of inclination of the rear slot 36 to the plane of travel of the trimmer is greater than the angle of inclination of the front slot 37, and, in practice, I prefer to make the said angle of the slot 36 about 20 45 degrees, and the angle of the slot 37 about 30 degrees. The parts projecting from the gage through the slots 36 and 37 are preferably a pivot screw 38, threaded into the gage, as shown more particularly in 25 Fig. 7, and having a head 39, of greater diameter than the width of the slot, so as to hold the head against the gage. Upon the body portion of each pivot screw there is mounted an antifriction roller 40, which 30 receives the thrust of the upper wall of the slot when the head is pressed downward in operating the trimmer, thereby preventing excessive friction between the head and gage. The head is held normally in its raised or 35 uppermost position by means of a spring 41, interposed between the head and gage, and arranged to act in a line which is substantially the general line of movement of the head relatively to the gage. The head is provided at its upper portion with a rearwardly 40 extending flange 42, which covers and protects the upper edge of the cutting disk, and with a thumb piece or hand rest 43 to receive the thumb, or ball of the thumb, of 45 the operator. The upper end of the spring 41 is seated in a recess 44, shown in dotted lines in Fig. 3, in the thumb piece 43, while its lower end is seated in a similar recess 45, also shown in dotted lines in Fig. 3, in a 50 .55 boss 46 on the gage 9.

The head 33 carries a cutting disk 47, which moves up and down with said head, so as to be projected below the plane of the bottom of the straight-edge when depressed, 55 said disk being supported in a bearing 48, projecting outward from the front face of the head in the form of a sleeve, preferably closed at its outer end. This bearing is located about midway between the slots 36 and 37, and it will therefore be seen that when 60 pressure is exerted downwardly upon the head, this pressure will be distributed to both the front and rear ends of the head, owing to the fact that the head is guided with relation to the gage at both of said 65 ends. The movement of the head and cutting disk is a combined downward and forward motion in the general direction of movement of the trimmer, so that pressure on the head in the natural direction required 70 to move the trimmer forward and at the same time move the cutting disk downward will effect the desired results with a maximum of efficiency. I prefer to give to the front slot a less angle of inclination than the 75 rear slot for the reason that this gives to the rear end or heel of the head an increased range of motion, this being the part thereof to which pressure is more directly applied. It results from the construction just described that the downward and forward 80 pressure applied to the head moves the cutting disk downward and forward toward the material to be operated on, so that it enters the same at an angle which gives a drawing cut, the efficiency of which is still further increased by the greater downward motion 85 of the rear part of the head.

The cutting disk 47 is secured in any suitable manner, as, for instance, by a screw 49, 90 to one end of an arbor 50, projecting from the bearing 48 within which it is mounted and supported. I provide means for supporting the cutting disk and its arbor with relation to said bearing in such a way that 95 the position of the cutter relatively to the head and straight-edge is determined through the medium of the bearing 48 without involving any end thrust or friction sufficient to materially affect the free rotation of the 100 cutter and its arbor, while at the same time the cutter and arbor may be readily detached from the head and as readily replaced, the parts positioning themselves automatically 105 when thus replaced and being held against 110 accidental displacement. The construction which I prefer for this purpose is shown more particularly in Fig. 5, in which the arbor 50 is shown as provided with a circumferential 115 groove 51, preferably semicircular in cross section. A detent pin 52 is mounted in the sleeve 48, its inner end, preferably rounded or hemispherical so as to fit the groove 51, projecting into the interior of the bearing 120 just sufficiently to engage the groove. The 125 head 53 on the outer end of the detent pin 52 serves, by its contact with the outer surface of the sleeve 48, to prevent said pin from being projected too far into the groove.

A spring 54 acts upon the detent pin 52 to 130 press the same inward. This spring may be of any suitable construction, and, in Figs. 1, 2, 5 and 10 I have shown said spring as a leaf spring in the form of an L, having its upright portion secured to the front face of the head

by a screw 55, while its free body portion extends over and bears on the head 53 of the detent pin 52. In Figs. 8 and 9 I have shown a modified form of this spring, in which it is 5 constructed as semicircular in form, as indicated at 56, being secured to the under side of the sleeve 48 at one end by a screw 57, while its free upper end bears on the head of the detent pin. The construction is such 10 that, while the inner end of the detent pin engages the groove in the arbor, it does not bear against the same with any material pressure, so that the rotation of the arbor and cutter are not impeded thereby. Furthermore, owing to the employment of this 15 detent, the cutting disk is held in proper relation to the other parts without any end bearings against the same. Thus, the sleeve 48 is made of such a length that when the 20 cutter is in operative position, the inner end of the arbor does not bear against the closed end of the sleeve, and, similarly, the disk itself does not need to bear against the other end of said bearing. Furthermore, this 25 construction permits of so positioning the cutting disk that it may be brought up against the front guiding surface 3 of the straight-edge without being pressed into contact with the same, so as to utilize said surface as a 30 guide for positioning the cutting disk, and the cutting disk is thereby permitted to move in a correct vertical plane without excessive friction against the face of the guide. It 35 will be at once seen that the disk and arbor can be removed from the head, when this latter is disconnected from the gage, by simply pulling outward on the disk, the detent pin yielding to permit the arbor to pass. In replacing the arbor and cutter, the detent 40 pin again yields and permits the arbor to pass inward until the detent pin enters the groove, whereupon the cutting disk will be automatically positioned with respect to the remaining parts. I am thus enabled to do 45 away with adjusting screws for positioning the disk, and am also enabled to reduce the frictional resistance to the rotation of the parts.

As already stated, the connection between 50 the cutting disk 47 and arbor 50 may be of any suitable description, but I prefer to employ the construction illustrated, which is of my invention. In this construction the screw 49 has a conical head 58, and the aperture in the end of the arbor into which the screw 50 fits, while threaded to receive said screw for the greater portion of its length, is provided with a tapering or conical recess at 55 its outer end to receive the similarly shaped screw head. The outer end of the arbor is 60 preferably reduced, as shown, to receive the cutting disk, which fits thereon against the shoulder thus formed, said reduced extension preferably extending through and

slightly beyond the disk. This reduced extension, in which is located the conical seat for the head of the screw, is transversely slotted, as indicated at 59, so that when the screw is turned home, with the disk in place, it will spread the end of the arbor and clamp 70 the disk firmly in position.

It is obvious that various modifications may be made without departing from the principle of my invention as specified in the appended claims. It is also obvious that all 75 of the various advantageous features hereinbefore described need not necessarily be embodied in a single structure.

Having thus fully described my invention, what I claim as new and desire to secure by 80 Letters Patent is:—

1. A straight-edge comprising a guide having lateral guiding surfaces, in combination with a cutting tool having guiding members provided with rollers which bear upon the 85 opposite lateral guiding surfaces of the guide, substantially as described.

2. A straight-edge comprising a guide having lateral guiding surfaces, in combination with a cutting tool having on one side two 90 separated guiding members and on the opposite side an intermediate guiding member, said guiding members being provided with rollers which bear upon the opposite guiding surfaces of the guide, substantially as de- 95 scribed.

3. A straight-edge comprising a guide having lateral guiding surfaces, one of the margins thereof being undercut or overhanging, in combination with a cutting tool having on 100 one side guiding members provided with rollers which bear against one of the lateral guiding surfaces of the guide and on the other side a guiding member having a vertical roller which bears upon the opposite guiding 105 surface of the guide, said last-mentioned guiding member extending under the overhanging margin of the guide, substantially as described.

4. A straight-edge comprising a guide having lateral guiding surfaces, one of the margins thereof being undercut or overhanging, in combination with a cutting tool having at 110 its opposite ends guiding members provided with rollers which bear upon the lateral 115 guiding surface on one side of the guide, an intermediate guiding member having a roller which bears on the opposite lateral guiding surface of the guide, said intermediate member engaging under the overhanging margin 120 of the guide, substantially as described.

5. A straight-edge comprising a guide having lateral guiding surfaces and an undercut or overhanging margin, in combination with a cutting tool having guiding members which 125 bear against said lateral guiding surfaces, one of said members engaging under the overhanging margin of the guide, and an anti-tilt-

ing member carried by the cutting tool and bearing on the straight-edge on the inner side of said guide members to prevent lateral tilting of the cutting tool, substantially as described.

6. A straight-edge comprising a guide having lateral guiding surfaces and an undercut or overhanging margin, in combination with a cutting tool having guiding members which bear against said lateral guiding surfaces, one of said members engaging under the overhanging margin of the guide, and a resilient anti-tilting member carried by the cutting tool and bearing on the straight-edge on the inner side of said guide members to hold the cutting tool upright with respect to the straight-edge, substantially as described.

7. A straight-edge comprising a guide having on its outer face a relatively wide lateral guiding surface, the opposite side of said guide consisting of an overhanging marginal portion with a relatively narrow lateral guiding surface, in combination with a cutting tool having on one side guiding members arranged to bear on the relatively wide guiding surface of the guide, and on the other side a guiding member bearing against the opposite guiding surface of the guide and engaging under the same, and an anti-tilting member carried by the cutting tool and bearing resiliently upon the straight-edge to hold the cutting tool upright with respect to the straight-edge and with its outer guiding members in parallel contact with the outer guiding surface of the guide, substantially as described.

8. A straight-edge having a guide with lateral guiding surfaces overhanging at its inner margin, in combination with a cutting tool having guiding members bearing on the lateral guiding surfaces, one of said members engaging under the overhanging portion of the guide, and a resilient anti-tilting member bearing on the straight-edge on the inner side of said guide members and connected to the cutting tool on its inner side, so as to resist lateral tilting in that direction, substantially as described.

9. A straight-edge longitudinally grooved and provided with a guide, in combination with a cutting tool having guiding surfaces coöperating with those of the guide and a lateral extension beyond the groove, a spring secured to said extension at one end, and a roller mounted in the other end of the spring and bearing upon the straight-edge back of the groove, substantially as described.

10. A straight-edge comprising a guide having lateral guiding surfaces and an undercut or overhanging margin, in combination with a cutting tool comprising a gage having guiding members which bear against said lateral guiding surfaces, one of said members engaging under the overhanging margin of the guide, and an anti-tilting member car-

ried by the gage and bearing on the straight-edge to prevent lateral tilting of the gage, and a head provided with a cutting disk and mounted on and guided by the gage, said head being movable in a vertical plane relatively to said gage, substantially as described.

11. A straight-edge having a guide, in combination with a cutting tool comprising a gage fitting and sliding on said guide and having vertical bearing surfaces on its front or outer face, and a head having a cutting disk and provided with vertical bearing surfaces on its inner face to coöperate with those of the gage, said head sliding bodily in a vertical plane with respect to the gage, and a spring interposed between the gage and head to lift the latter, substantially as described.

12. A straight-edge having a guide, in combination with a cutting tool comprising a gage fitting and sliding on the guide, and a head provided with a cutting disk and mounted to slide on the gage in a downward and forward direction, substantially as described.

13. A straight-edge provided with a guide, in combination with a cutting tool comprising a gage fitting and sliding on the guide, and a head mounted to slide on the gage in a downward and forward direction, the rear portion of said head having a more rapid downward movement than the front portion, substantially as described.

14. A straight-edge provided with a guide, in combination with a cutting tool comprising a gage fitting and sliding on said guide, and a head provided with a cutting disk, one of said members having downwardly and forwardly inclined slots, and the other of said members having projections entering said slots, whereby the head is guided with a downward and forward movement relatively to the gage, substantially as described.

15. A straight-edge provided with a guide, in combination with a cutting tool comprising a gage fitting and sliding on said guide, and a head provided with a cutting disk, one of said members having downwardly and forwardly inclined slots, and the other of said members having projections entering said slots, whereby the head is guided with a downward and forward movement relatively to the gage, the angle of inclination of the rear slot to the horizontal being greater than the angle of inclination of the front slot, whereby the downward movement of the rear end of the head is accelerated, substantially as described.

16. A straight-edge having a guide, in combination with a gage fitting and sliding thereon, and a head having a cutting disk centrally mounted thereon, said gage and head having coöperating inclined guiding slots and projections located on opposite sides of the cutting disk, substantially as described.

17. A straight-edge having a guide, in combination with a gage fitting and sliding on said guide, and a head provided with a cutting disk, the meeting faces of the head and gage having coöperating vertical bearing surfaces, the head being provided near its ends with downwardly and forwardly inclined slots, and the gage having guiding projections extending through said slots and provided with retaining heads of greater width than the slots to hold the head against the gage, substantially as described. 65
18. A straight-edge having a guide, in combination with a gage fitting and sliding thereon, and a head carrying a cutting disk, one of said members being provided with inclined guiding slots at its end and the other of said members being provided with guiding projections having anti-friction rollers fitting said slots, substantially as described. 70
19. A straight-edge having a guide, in combination with a cutting tool comprising a gage fitting and sliding on said guide, and a head having a cutting disk centrally mounted thereon, said head and gage having coöperating vertical bearing surfaces, said head having at its ends downwardly and forwardly inclined slots, pivot screws passing through said slots threaded into the gage and having their heads bearing against the outer surface of the main head to hold the same against the gage, and antifriction rollers mounted on said pivot screws in said slots, substantially as described. 75
20. A straight-edge having a guide comprising a lateral guiding surface on the front edge of the straight-edge, in combination with a cutting tool comprising a gage adapted to slide on said guide and a head vertically movable with respect to the gage, said gage having a portion interposed between the head and the front guiding surface of the straight-edge, said portion bearing on one side against said guiding surface and having on the other side a bearing surface against which the head bears, substantially as described. 80
21. A cutting tool comprising a head having a bearing sleeve, and a spring-actuated detent extending into the interior of said sleeve, in combination with a cutting disk having an arbor removably fitting said bearing sleeve, said arbor having a circumferential groove adapted to be engaged by the detent to position the cutting disk relatively to the head, substantially as described. 85
22. A cutting tool comprising a head having a bearing sleeve, and a spring-actuated detent extending into the interior of said sleeve, in combination with a cutting disk having an arbor removably fitting said bearing sleeve, said arbor having a circumferential groove adapted to be engaged by the detent to position the cutting disk relatively to the head, said detent yielding automatically to permit removal and insertion of the arbor, substantially as described. 90
23. A cutting tool comprising a head having a bearing sleeve, and a spring-actuated detent extending into the interior of said sleeve, in combination with a cutting disk having an arbor removably fitting said bearing sleeve, said arbor having a circumferential groove adapted to be engaged by the detent to position the cutting disk relatively to the head, and means for limiting the inward movement of the detent to prevent excessive friction thereof against the arbor, substantially as described. 95
24. A cutting tool comprising a head having a bearing sleeve, a detent pin extending through said sleeve having its inner extremity lying within said sleeve, and having at its outer end a head which limits the inward motion of the pin, a spring acting on said pin to move it inwardly, a cutting disk, and an arbor carrying said cutting disk and removably fitting the bearing sleeve, said arbor having a groove to receive the inner extremity of the pin, said groove and the extremity of the pin being so constructed as to cause the pin to yield outwardly when sufficient force is applied in a longitudinal direction to the arbor, substantially as described. 100
25. In a cutting tool of the character described, a centrally apertured cutting disk, in combination with an arbor having a reduced end to receive said disk and a shoulder against which the disk fits, said extension being transversely slotted, said arbor having a longitudinally threaded aperture terminating at its outer end in a tapering or conical recess within the reduced extension of the arbor, and a screw threaded to fit said aperture and having a conical head to fit said recess, substantially as described. 105
26. In a paper cutter, the combination of a casing or frame supporting a disk, and a gage piece loosely attached thereto, said attachment being formed by inclined slotted guides on one part adapted to fit over projections in the other part, and a spring between the gage and casing, substantially as specified. 110
27. The combination with a casing supporting the disk and the gage attached thereto, diagonal slots in the casing, and rollers secured to the gage and fitting in said slots, and a spring between the casing and gage, for the purpose specified. 115
28. In a paper cutter, the combination of a disk and a casing, a supporting frame for said casing, in relation with which said disk and casing are slidingly mounted, and means for directing the sliding movement of said disk and casing simultaneously downwardly and forwardly in relation to said supporting frame, substantially as described. 120
- 125

29. In a paper cutter, the combination of a disk and a casing therefor, parallel inclined guides formed in said casing, a supporting frame, projections thereon engaging said inclined guides, and a spring between said supporting frame and casing, substantially as described.

In testimony whereof, I affix my signature in presence of two witnesses.

CHARLES T. RIDGELY.
